UNITED STATES PATENT OFFICE.

EDGAR W. MYERS, OF SAN JOSE, CALIFORNIA, ASSIGNOR, BY MESNE ASSIGNMENTS, TO
MASTERROLL PERFORATING MACHINE COMPANY, OF LOS GATOS, CALIFORNIA, A
CORPORATION OF CALIFORNIA.

PAPER-FEED.

1,211,615.

Specification of Letters Patent.

Patented Jan. 9, 1917.

Application filed April 25, 1914. Serial No. 834,447.

To all whom it may concern:

Be it known that I, EDGAR W. MYERS, of San Jose, in the county of Santa Clara, and in the State of California, have invented a certain new and useful Improvement in Paper-Feeds, and do hereby declare that the following is a full, clear, and exact description thereof.

My invention relates to machines for making perforated sheet music and in particular to paper or sheet feeding mechanism, and among other objects my aim is to provide a sheet feeding mechanism which will dispense with the employment of feed rollers over the periphery of which the paper must be carried or passed; will be adjustable to suit paper of different widths; admit of such adjustment that the perforated sheet may be longer or shorter than the master sheet; and withal will be simple in construction with the advantages coming from simplicity of reduced cost of construction and freedom from liability to get out of order, and to these ends and to others, which will be evident to those skilled in the art, my invention consists in the mechanism constructed substantially as hereinafter specified and claimed.

In the accompanying drawings, Figure 1 is a vertical longitudinal section of enough of a perforated music making machine to show an embodiment of my invention; Fig. 2 is a top plan view of the feeding mechanism; Fig. 3 is a vertical section on the line 3-3 of Fig. 2, the full lines showing the position of parts for feeding paper of one width, and the dotted lines showing the position of parts when adjusted to feed narrower paper; Figs. 4 and 5 are detail views of one of the paper clamps; Fig. 6 is a detail view in cross section of the latch for the clamp actuating rail; Fig. 7 is a detail view of the ratchet-operating mechanism.

Briefly described, the machines to which my invention has been especially adapted have a punching or perforating mechanism whose action is automatically controlled by a perforated master sheet. It is not necessary to describe in detail the punching mechanism, it being sufficient to explain that the sheet S to be perforated passes horizontally to dies 10 and punches 11 and to call attention to Patent No. 984,289, issued February 14, 1911, for a disclosure of the details of a suitable punch operating and controlling

mechanism. The paper to be punched after passing between the punches and dies is engaged by my feeding mechanism and by the latter is fed or drawn along step by step coming from a roll (not shown) and being guided upward and horizontally over a guide plate 12 secured to the frame of the machine. My feeding mechanism is mounted upon a frame that comprises similar side plates 13 which are bolted to the machine bed plate, and transverse bars or bolts 14 which rigidly space the side pieces apart and maintain them in fixed relation to each other, one of these cross bolts being at one end of the frame and serving as a stationary shaft to support and about which may freely turn two sprocket wheels 15. At the other end of the frame in a position corresponding with that of said end bolt, is journaled in suitable bearings a driving shaft 16 having two sprocket wheels 17 which respectively align with the sprocket wheels 15 on said transverse bolt or stationary shaft connecting the pair of alining sprocket wheels is a sprocket chain 18 which at regularly spaced intervals on its outer side is provided with paper-gripping devices each in the form of a block 19 that is fixed to the chain, and a block 20 pivoted at one edge to the chain attached block so that by the swinging of the pivoted block the edge of the paper may be clamped, or gripped between the two blocks, or released therefrom. A coil spring 21 conveniently mounted on the pivot pin of the paper clamp acts normally to swing the pivoted block out of contact with the edge of the paper, and as is hereinafter explained, means are provided which cause automatically the movement of the pivoted block against the action of its spring so as to clamp, or grip the edge of the paper between the two blocks, at which time the paper partakes of the movement of the grip, or clamp with its chain and the feed of the paper is caused. Preferably the paper-engaging faces of the two blocks are covered with leather, or other friction producing material which will securely grip the paper without injury to it.

Each of the hinged blocks of the paper gripping device has projecting from its edge opposite its hinge a pin or stud 22, and these pins or studs are adapted to engage, as they are moved along with the chain, with a horizontal rod, or rail 23 which is sup-

ported sufficiently close to the paper that the pivoted blocks will be swung on their pivots toward their respective fellow clamping members and thereby the paper gripped, 5 or clamped, such gripping of the paper continuing so long as the pins, or studs remain in contact with said rail. The end of the rail toward which the blocks move is curved outward and upward to provide a cam surface 10 face 24 which is in the path of the block pins, or studs, which before they come in contact with the rail are in a vertical position so that by the action of such cam on the pins, or studs, the blocks are swung downward to 15 grip, or bind the paper, as has been explained. The rail is preferably of such length that several clamps at a time are in contact therewith so that the paper at the same time is gripped at several separated 20 points and thus the advantage of drawing the paper along by having engaged at several points along its edge rather than one point, is secured.

The clamp actuating rail is movably 25 mounted so that it may be moved to release the clamps, as when a new sheet of paper is to be used, so as to facilitate, or enable the "threading" of the paper in the clamps, but normally the rail is maintained in a position 30 where it is ready to act upon the movable members of the clamps to cause their engagement with the paper and at the proper time their automatic release from the paper when by the travel of the chain the clamps 35 are carried out of contact with the rail. Each rail at its opposite ends has an arm 25 which extends substantially at right angles to the rail and is passed through a diametrically extending hole near the end of a horizontal rock shaft 26 which is journaled in bearing lugs 27 on the outside of and near the ends of a frame plate 28 through which the end cross bars 14 and the driving shaft 16 pass, said frame plates being thus supported. Entering each end of the rock shaft 40 is a set screw 29 which impinges upon the portion of the arm 27 therein and thus an adjustable mounting of the rail is secured which enables such adjustability of the rail 45 as may be necessary to secure the desired clamping action of the clamps. Near each bearing lug the rock shaft has a short coil spring 30, which at one end is fixed to a bearing lug 27 and at the other end engages 50 a set collar 31 fixed to the shaft, which springs constitute the means for normally holding the rail in position to act upon the clamps. At midlength the rock shaft has a radial handle 32 by which it may conveniently be turned to lift the rail from its 55 position to act upon the clamps and as a convenient means of holding the rail in such lifted position while leaving the hands free to place the paper, I provide a spring-actuated latch stud 33 that passes through a hole

in one of the bearing lugs 27 and enters a hole 34 in the rock shaft when the latter is turned sufficiently to lift the rail to the desired extent. The upper side of each frame plate 28 has a longitudinal groove or channel formed by parallel vertical ribs 35 to confine the chain-carrying blocks of the clamps against lateral movement, and the outer edges of said blocks are overhung at the top by a horizontal flange 36 on the outer 75 vertical rib 35. Thus displacement of the clamps while acting upon the paper is impossible. The space between the two frame plates is bridged by a plate 38 which forms a supporting table, or surface for the paper 80 as it is fed along, and said plate is removable because to suit the machine for feeding paper of different widths the plates are adjustable toward and from each other, and hence, for paper of different widths plates 85 of different widths must be employed. Each frame plate 28 is forked or bifurcated at its end so as to straddle at each end one of the sprocket wheels and the sprocket wheels being thus embraced and confined by the forks of the plates it will be seen that when the plates are shifted to adjust them for different widths of paper the sprocket wheels, and their chains are likewise shifted. The driving shaft 16 is provided with a keyway 90 and each sprocket wheel thereon has a key, or spline that enters said keyway so that by the revolution of the shaft both sprocket wheels are revolved and they are so revolved whatever be the position to which they may 100 be shifted along the shaft. To secure the frame plates and all the parts which move therewith in the desired position of adjustment, I place upon the driving shaft at one side of each of the sprocket wheels thereon 105 a collar 37 which preferably is splined to the shaft and which has a set screw 38 by which the collar may be fixed to the shaft and thus the parts restrained in the position to which they may be set or adjusted. 110

On the underside of each frame plate is attached a horizontal bar or rod 39 in position to be engaged by the pins or studs of the hinge members of the clamps, and each of said rods inclines inward so that as the clamps move along with the chain the rods will act to swing the movable members of the clamps on their pivotal connections with the fixed clamp members, and thus prevent their contact with underlying portions of 115 the machine at this point.

For imparting a step by step, or intermittent motion by the feeding mechanism, I place upon one end of the driving shaft a ratchet wheel 40, the teeth of which are engaged by 120 a feeding pawl 41 carried by an arm 42 hung upon the shaft and which is connected by a link, or pitman 43 that has a lever 44 pivoted on the end cross bolt 14 of the frame. Said lever 44 is connected by a pitman 45 125

with one end of an eccentric rod 49 whose other end is connected with an eccentric 47 on the punch operating shaft 48 of the perforating machine and the same eccentric 5 rod is connected with a ratchet lever 50 of the feed roll 51 by which the master sheet is fed in the operation of the perforating machine. The pitman 45 and lever 50 which at their ends are connected with the eccentric 10 rod, have a toggle-like relation so that as the eccentric rod 49 moves back and forth the respective levers 44 and 50 are vibrated. For preventing back motion of the ratchet wheel, a dog, or pawl 52, is provided. By 15 changing the ratchet wheel for one of different diameter, for example, one smaller, it will be seen that the travel of the carrier chains will be shortened and the same result can be secured by changing the stroke of the 20 feeding pawl carrying arm. Thus, as the feed of the master sheet is connected with the feed of the paper to be punched, it will be seen that a perforated sheet that is a duplicate in all respects of the master sheet, 25 may be produced, or by changing the extent of the paper feed a perforated sheet, either longer or shorter than the master sheet may be produced.

It will be seen that danger, or likelihood 30 of slippage of the paper is eliminated by my feeding mechanism, both by reason of the fact that each edge of the paper is gripped, or clamped by the feeding devices at several separated points and by reason 35 of the form of the paper-engaging means which have a positive hold upon the paper. It is obvious that several sheets at a time may be passed through the machine for the 40 clamps can adequately grip several thicknesses of paper. It will be observed that the feeding movement is a step by step one and not continuous, so that the paper is stiffer while being perforated. Should the jaws of 45 a clamp tend to stick together at a point just before they reach the position in their return movement for engaging the oncoming paper, their pins or studs 22 may be engaged by cams or guides which will force the movable jaw to an open position ready 50 for the paper.

While I prefer to embody my invention in the construction shown in the drawings, yet, it is to be understood that it is possible without departure from my invention to 55 otherwise embody it.

Having thus described my invention what I claim is—

1. The combination of a frame, a driving shaft, means for imparting motion to the 60 driving shaft, traveling sheet clamping devices situated to engage opposite sides of the sheet, means for imparting motion to said devices from said shaft, and supports for said devices, one being shiftable toward

and from the other to adjust for sheets of 65 different width.

2. The combination of a frame, a driving shaft, means for imparting motion to the driving shaft, endless carriers receiving motion from said driving shaft, a series of sheet 70 clamping devices spaced along each of said carriers, said clamping devices having each a movable jaw, means in the path of travel of said jaws to actuate the same, and a support for one of said endless carriers which 75 is shiftable toward and from the other endless carrier to adjust the distance from carrier to carrier between their sheet-clamping device to adjust for sheets of different width.

3. The combination of a frame, a driving 80 shaft, means for imparting motion to the driving shaft, endless carriers receiving motion from said driving shaft, a series of sheet clamping devices spaced along each of said carriers, said clamping devices having 85 each a movable jaw, a spring for each jaw acting to move it to an open position, a rail contiguous to the path of travel of the movable jaws that is engaged by them to move them in opposition to the action of 90 their springs, a support for one of said endless carriers and for said rail, which is shiftable toward and from the other endless carrier to adjust the distance from carrier to carrier between their sheet-clamping 95 device to adjust for sheets of different width.

4. The combination of a frame, a driving shaft, means for imparting motion to the driving shaft, traveling sheet clamping devices situated to engage opposite sides of 100 the sheet, means for imparting motion to said devices from said shaft, and supports for said devices through which the shaft passes that are shiftable toward and from each other along the shaft. 105

5. The combination of a frame, a pair of shafts supported thereby, one of said shafts being a driving shaft, wheels on the shafts, endless carriers connecting the wheels of the respective shafts, sheet clamping devices mounted on said carriers, and frame plates slidably mounted on the two shafts and straddling the respective wheels on the shaft whereby shifting of the plates is accompanied by shifting of the wheels and 110 their carriers.

6. The combination of a series of sheet clamps each having a movable member, means for moving said clamps along, a rail contiguous to the path in which said clamps 115 move situated to act upon the movable members thereof, and means to move said rail out of such situation.

7. The combination of a series of sheet clamps, each having a movable member, 120 means for moving said clamps along, a rail contiguous to the path in which said clamps move situated to act upon the movable mem-

bers thereof, and a spring actuated rock shaft to which said rail is connected.

8. The combination of a series of sheet clamps, each having a movable member, means for moving said clamps along, a rail contiguous to the path in which said clamps move situated to act upon the movable members thereof, a spring actuated rock shaft to which said rail is connected, said rock shaft being normally held in a position to present the rail in clamp-operating position, means to turn said shaft to move said rail from such position, and a latch device to hold the rock shaft in the position to which it may be turned.

9. The combination of a series of sheet clamps, each having a movable member, means for moving said clamps along, a rail contiguous to the path in which said clamps move situated to act upon the movable mem-

bers thereof, and a spring actuated rock shaft to which said rail is adjustably connected.

10. The combination of master sheet feeding means, paper feeding means, each of said means being a pawl and ratchet mechanism, a common operating mechanism for said two feeding means, means to vary the relative feed thereof, said operating mechanism including a reciprocating rod and a toggle-like connection between said two pawl and ratchet mechanisms with which said rod is connected, and perforating mechanism.

In testimony that I claim the foregoing I have hereunto set my hand.

EDGAR W. MYERS.
